UNITED STATES PATENT OFFICE.

FRITZ BALZER, OF MOLINE, ILLINOIS, ASSIGNOR TO TROY LAUNDRY MACHINERY CO., LTD., OF CHICAGO, ILLINOIS, A CORPORATION OF NEW YORK.

CONTROL MECHANISM.

Application filed September 10, 1924. Serial No. 736,817.

To all whom it may concern:

Be it known that I, FRITZ BALZER, a citizen of the United States, residing at Moline, in the county of Rock Island and State of Illinois, have invented certain new and useful Improvements in Control Mechanism, of which the following is a specification.

The present invention relates to control mechanism.

10 The present invention relates to the subject matter of the application for United States Letters Patent filed November 22, 1923, Serial No. 676,287, filed by the present applicant, and will be described in connection with mechanism similar to that referred to in said prior application.

Before proceeding with a statement of the objects of the present invention and a description of said invention it may be 20 stated that the invention is particularly applicable to devices in which it is desirable to bring a moving member to rest at a predetermined point without undue shocks and without requiring particular skill upon the 25 part of the operator. Such mechanism is represented in the rotary cylinder of a washing machine. As is well known, common types of washing machines comprise an outer casing or shell which encloses a rotary cylinder. Said cylinder encloses the 30 goods to be washed and, in order to permit insertion and removal of said goods, said cylinder is ordinarily provided with a door. The enclosing casing or shell is also provided with a door to permit access to the 35 interior of the cylinder through the shell or casing. In order to bring the rotary cylinder to a stop in such a position that access to the cylinder door may readily be had 40 through the casing door, various control means have been devised. In certain common types of rotary cylinder washing machines means have been provided whereby the cylinder after rotating a predetermined 45 number of revolutions in one direction is automatically reversed in direction and after a predetermined number of revolutions is again reversed, this reversing process being maintained throughout the wash- 50 ing operation. With certain control devices, if handled by an unskilled operator it frequently happens that just as the operator is attempting to bring the rotary cylinder to a stop in the proper position by inching same 55 toward said position, the automatic mecha-

nism for reversing the direction of rotation of the cylinder will perform its function, baffling the efforts of the unskilled operator. Said rotary cylinders are commonly provided with partitions, arranged diamet- 60 rically or radially thereof, dividing the cylinder into two or more compartments, the individual compartments being disposed about the axis of the cylinder. In order to

provide access to each compartment, it is 65 necessary to stop the cylinder at a different position for each compartment. Washing machines are commonly provided with mechanism which renders it impossible to rotate the cylinder unless the door of the 70 enclosing casing or shell is closed. In the case of a rotary cylinder having a plurality of compartments as above referred to, it is a tedious operation to close the casing or shell doors when it is required to rotate the 75

cylinder a fractional part of a revolution, particularly if the stopping of the cylinder rotation is controlled by means of automatic mechanism, which is necessarily slower of 80 operation than is desired when movement through only a fractional part of a revolution is required. The present application is a continuation as to common subject matter 85 of the prior application above referred to.

The above example is chosen as an illustration to indicate the sort of problem which applicant has solved by the present invention. It will be understood as the description proceeds, however, that the invention 90 is not limited to washing machines or to any particular type of machine, but is of much broader application.

An object of the present invention is to provide control mechanism for automatically bringing a moving member to a stop in a predetermined position.

A further object is to provide control mechanism applicable to the rotary cylinder of a washing machine for automatically bringing said cylinder to a stop at a predetermined position.

A further object is to provide control mechanism which upon a simple actuation of a single member will control the movement of a moving member to slow down the speed of said member and thereafter to positively bring said member to a stop at a predetermined position.

A further object is to provide automatic stopping mechanism for bringing a mem-

ber to a stop at a predetermined position with a minimum of shock.

A further object is to provide control mechanism applicable to the rotary cylinder 5 of a washing machine for automatically bringing said cylinder to a stop at a predetermined position, said mechanism including means by which the ordinarily provided electrical interlock between the cylinder and 10 the enclosing casing may be shunted when desired.

Further objects will appear as the description proceeds.

Referring to the drawings—

15 Figure 1 is a sectional view of control mechanism embodying the principles of the present invention;

Figure 2 is a view taken along the plane indicated by the arrows 2—2 of Figure 1;

20 Figure 3 is a view illustrating the position of certain operating parts under running conditions;

Figure 4 is a view of the parts shown 25 in Figure 3 after a simple actuating movement has been imparted to a member constituting part of the control mechanism but before any speed changes have been accomplished;

Figure 5 is a view showing the parts in 30 an intermediate stage during the stopping operation;

Figure 6 shows the parts at the moment when stoppage has been accomplished;

35 Figure 7 illustrates a detail of the actuating mechanism, being a view taken along the plane indicated by the arrows 7—7 of Figure 1;

Figure 8 indicates certain switch mechanism;

40 Figure 9 represents diagrammatically an electrical circuit which is illustrative of electrical circuits which may be used in connection with the present invention; and

45 Figure 10 represents more or less diagrammatically a washing machine cylinder provided with a plurality of compartments disposed around the axis of the cylinder.

The numeral 11 indicates a housing which 50 may be provided with the cover 12. Mounted outside of the cover 12 is the handle 13, which is adapted to have a swinging movement about the axis of the shaft 14. The outer side of the cover 12 may be provided with abutment means taking the 55 form of ratchet teeth, said abutment member being indicated by the numeral 13'. The handle 13 may be provided with spring-pressed control mechanism which will yieldingly hold the handle 13 in predetermined 60 positions relative to the cover 12, several of said positions being shown in Figures 3 to 6 inclusive. The details of the spring-pressed mechanism cooperating with the handle 13 need not be described in detail 65 herein inasmuch as structures suitable for

the purpose are well known to those skilled in the art and inasmuch as such details form no part of the present invention. It may be stated, however, that the handle 13, though 70 yieldingly held in a predetermined position, may be readily moved by means, to be referred to hereinafter, from said predetermined positions to an adjacent predetermined position. The numeral 15 indicates a stop member fixed with reference 75 to the cover 12 and the numeral 16 indicates a pointer rigid with respect to the handle 13 for convenience in indicating the position of said handle 13.

The handle 13 is fixedly mounted upon 80 the sleeve 17, which is rotatably mounted in the cover 12, which sleeve, as the parts are viewed in Figure 1, extends to the left to the plane indicated by the numerals 7—7 in said Figure 1. Fixedly mounted upon 85 the sleeve 17, as for example by means of a key 18 which is held in place by a set screw 19, is the escape lever 20. Said escape lever 20 has the function when the handle 13 is in a predetermined position, which, for convenience, may be termed the running position, to hold the weight lever 21 in a predetermined position, as shown in Figure 3. Said weight lever 21 is fast upon the shaft 22, which extends in a line substantially 90 parallel with the shaft 14. The shaft 22 has rigidly mounted thereon the pawl 23 adapted to have cooperative relationship with the ratchet segment 24. The ratchet segment 24 is fixedly mounted upon the 95 sleeve 25, which extends to a boundary marked by the right-hand face of the boss 26 forming part of the ratchet segment 24 as the parts are viewed in Figure 1. Also 100 fixedly mounted upon the sleeve 25 is the lever arm 27, which carries the roller 28 adapted to cooperate with the cam member 29. The cam member 29 may move in synchronism with a moving member to be controlled. Referring to washing machines, 105 said cam member 29 may be mounted to rotate with the cylinder of a washing machine. Said cam member 29 is provided with a plurality of raised portions corresponding 110 to the compartments of a washing machine cylinder. One of said raised portions is illustrated in Figures 2 to 6 inclusive and is indicated by the numeral 30. Said raised 115 portions 30, as the cam 29 rotates, will operate the lever 27 to communicate motion to the sleeve 25 and ratchet segment 24. The shaft 22 is rotatably mounted upon 120 the lever 31. Said lever 31 is bifurcated, having the two legs 32 and 33, the leg 32 being rotatably mounted upon the sleeve 25 and the leg 33 being fixedly connected to the shaft 14. The upper portion of the lever 31 is also bifurcated to provide arms 34—34, which carry the pin 35 for pivotally 125 mounting the rod 36, which may control 130

brake mechanism cooperating with the member whose speed is to be controlled, namely, the member in synchronism with which the cam 29 rotates, that is, in the illustration chosen for this description, the washing machine cylinder. It will be clear that when the cam 29 is rotated, engagement of the high portions 30 of said cam with the roller 28 will result in an oscillating movement 10 of arm 27, which oscillating movement will be communicated to the ratchet segment 24. If the pawl 23 is in a position to cooperate with the ratchet segment 24, the net result of the oscillation of the arm 27 will be a 15 step-by-step movement of pawl 23 and lever 31 in a left-hand direction as the parts are viewed in Figures 2 to 6 inclusive. Fixedly mounted upon the lever 31 is the electrical control block 37, which may have an arcuate surface having the center line of shaft 14 as an axis. The arcuate surface of the central block 37 carries the contact members 38 and 39, which are adapted to be selectively engaged by the contact fingers 40, 41, 42 and 43, which contact fingers may be supported in any preferred way within the housing 11. The electrical connections of the contacts 38 and 39 and the contact fingers 40, 41, 42 and 43 need not be described in 20 detail herein, nor need the circuits controlled thereby be described, it being sufficient to state that when the contact members and the contact fingers are in one predetermined relationship the circuit through the driving 25 motor for the cam 29 will be open; in another relationship said circuit will be connected to provide a low speed for said driving motor; and in another relationship said motor will be connected for full speed. 30 Fixedly mounted upon the shaft 14 is the lever 44 adapted to yieldingly control movement of the handle 13. Details of this control do not form any part of the present invention. It may be stated, however, that 35 when the shaft 14 is rotated, said lever 44 will yieldingly carry the handle 13 through the degree of movement imparted to said shaft 14.

From an inspection of Figure 7 it will be 40 clear that the hub portion of escape lever 20 and the hub portion of the leg 33 of lever 31 are provided with abutting portions 45 and 46, which abutting portions limit relative rotation between said escape lever 45 and lever 31. The construction of the 50 abutting portions 45 and 46 affords lost motion between said escape lever 20 and lever 31, which lost motion is indicated by the angle X in Figure 7.

Figure 9 indicates an electrical circuit 55 which may be used in connection with the rotary cylinder of a washing machine or in connection with other mechanism whose motion is to be controlled. The numeral 47 indicates a driving motor and the nu- 60 meral 48 indicates a switch box. The numeral 49 indicates certain control mechanism for varying the connections to motor 47, which control mechanism 49 may be operated by the electrical motor 50, which may receive its energization from any preferred source. The numerals 38 and 39 indicate the contact members illustrated in greater detail in Figure 8, and the contact fingers 40, 41, 42 and 43 are shown in cooperation 70 with said contact members 38 and 39. The numeral 51 indicates an electric switch controlled by the door of the enclosing shell or casing. Such a switch is commonly provided upon washing machines of the rotary 75 type for preventing the rotation of the cylinder until said shell or casing door is closed. The numerals 52—52 indicate power lines leading to the switch box 48. 80

Figure 10 illustrates more or less diagrammatically a multi-compartment cylinder mounted within a casing. Said cylinder, which is indicated by the numeral 53, is provided with the radially disposed partitions 54—54 providing three compartments 90 disposed around the axis of rotation of said cylinder. Access to each of said compartments is had through the doors 55—55, which doors may be hinged on axes 56—56 disposed parallel with the axis of rotation of the cylinder. The enclosing shell or casing for the cylinder 53 is indicated by the numeral 57. Said shell or casing is provided with the door 58. The door 58 is illustrated as being swingingly mounted, 95 but it will be understood that the particular mounting of the shell door is immaterial insofar as the present invention is concerned. Said door 58, however, as indicated above, controls the electric switch 51. 100 When said door 58 is in open position the switch 51 will be held in its open position as indicated in Figure 9. When the door 58 is in closed position the switch 51 will be in closed position. Shunting the switch 51 is the switch 59, which may be manually operable. It will be clear that by operation of the switch 59 the controlling circuits of the washing machine may be controlled independently of the switch 51, that is to say—individually of the door 58 of the enclosing shell or casing. 110

In explaining a mode of operation of the above described embodiment of the present invention a brief outline of the function of the electrical circuits shown in Figure 9 will be given. 115

The circuits of the driving motor 47 may be controlled by switches located within the switch box 48, the manner in which said switches operate needing no detailed description herein, it being sufficient to state that switch mechanism is well known which will control a motor to cause said motor to 120 rotate in one direction for a predetermined 125 time. 130

number of revolutions and then reverse its movement for a predetermined number of revolutions, proceeding through this cycle as long as certain predetermined connections are maintained. Switch mechanism is also well known having the function of causing the motor to run at different speeds or to be unenergized. For the purpose of changing the connections to the motor 47 to produce changes in the direction of the rotation of a washing machine cylinder, as above described, the controller 49 may be driven by the small motor 50. For the purpose of controlling the speed of the electric motor 47 the electric switch mechanism comprising the members 38 and 39 and the contact fingers 40, 41, 42 and 43 are provided.

As referred to above, the connections of said contact fingers 40, 41, 42 and 43 will be controlled in response to the movement of the control block 37, which, as will be explained in detail hereinafter, is responsive to the action of ratchet segment 24 and the pawl 23. In the position illustrated in Figure 9 all of the contact fingers 40, 41, 42 and 43 are disconnected from circuit and the driving motor 47 will be deenergized. When the contact members 38 and 39 have been moved to a position in which the contact fingers 41 and 42 are bridged by contact member 39, a relatively slow speed of rotation will result in the electric motor 47. When contact members 38 and 39 have been moved to a position in which contact fingers 40 and 41 are bridged by contact member 38 and contact fingers 42 and 43 are bridged by contact member 39, full speed of the electric motor 47 will result.

When it is desired to produce normal operation of the moving mechanism carrying the cam 29, which, for convenience, in this specification has been referred to as a washing machine cylinder, the handle 13 will be moved to the position indicated in Figure 3. The handle 13 is rigidly united to the escape lever 20 and when the handle 13 is in the position shown in Figure 3, said escape lever 20 will be held in a substantially vertical position. In this position the escape lever 20 abuts against the weight lever 21 so that said weight lever is held out of its depending position. The weight lever 21 is rigidly united to the pawl 23 and at this time said pawl 23 is held out of engagement with the teeth of the ratchet segment 24. By reason of the abutting relative position between the portions 45 and 46 of the escape lever 20 and the lever 31 respectively, movement of the handle 13 to its position shown in Figure 3 will have caused said lever 31 to move in a clockwise direction, as indicated in Figure 3, to the position shown. By reason of the lost motion between escape lever 20 and lever 31, which lost motion is indicated by the angle X in Figure 7, the le-

ver 31 will lag behind handle 13 by the angularity indicated by said letter X. When the handle 13 is in the position referred to, that is—the position shown in Figure 3, the rod 36 will be held over in its right-hand position whereby to cause the release of the brake mechanism controlled by said rod. At this time, also, the switch mechanism mounted upon the holder 37 will be at its limit of clockwise movement, whereby the spring fingers 41 and 42 will be in engagement with the contact member 38 and the spring fingers 42 and 43 will be in engagement with the contact member 39. The conditions immediately above referred to are those for producing normal operation of the mechanism carrying the cam 29.

When it is intended to stop the rotating mechanism including the cam 29, the operator will move the handle 13 in a counterclockwise direction through the angle X to the position shown in Figure 4. By reason of the lost motion between the abutment portions 45 and 46 of the escape lever 20 and lever 31 respectively, said movement of handle 13 in a counterclockwise direction will have no immediate effect upon said lever 31 or the rod 36 connected to said lever 31.

The movement referred to will, however, withdraw the escape lever 20 from holding relationship with the weight lever 21, whereby the pawl 23 rigidly connected to said weight lever 21 will be allowed to gravitate to a position in which said pawl 23 has cooperative relationship with the ratchet segment 24. As explained above, the ratchet segment 24 is rigidly united to the rocker arm 27 which cooperates with the cam 29 of the member to be controlled. As said cam 29 rotates, any one of the high portions 30 thereof, whenever said high portion comes in contact with the roller 28, causes an oscillating movement of the arm 27 and ratchet segment 24. Figure 4 represents conditions after the handle 13 has been moved through the angle X but before a high portion 30 of the cam 29 has operated the arm 27.

Figure 5 represents conditions at the instant that a high portion 30 of cam 29 has raised the arm 27 to the limit of its movement. This upward movement of the arm 27 as the parts are viewed in Figures 3 to 6 inclusive, causes the actuation in a counterclockwise direction of the ratchet segment 24, which ratchet segment moves the pawl 23 and lever 31 in a counterclockwise direction to the position shown in Figure 5. Inasmuch as the lever 31 is rigidly connected to the shaft 14, which shaft 14 carries the lever 44, the net result of moving the lever 31 to the position shown in Figure 5 will be actuation of lever 44. As explained above, lever 44 is connected to handle 13 to

control same so that actuation of lever 44 will result in actuation of handle 13 to a substantially vertical position, as shown in Figure 5. Movement of lever 31 results in the pulling of rod 36 as viewed in Figure 5, whereby to lightly apply the brake mechanism controlled by said lever. The switch mechanism carried by the switch block 37, which block is mounted upon the shaft 22 connected with lever 31, will not be in the position indicated in Figure 8, in which contact fingers 41 and 42 engage with the switch contact 39 and contact fingers 40 and 43 are disconnected from circuit. These connections may be utilized to slow down the speed of the motor 47 which drives the mechanism moving in synchronism with the cam 29. In case the control mechanism forming the subject matter of the present invention is used in connection with washing machine cylinders of the reversing type, said changed electrical connections may be utilized to eliminate the reversing feature whereby to insure against the possibility of the washing machine cylinder reversing its direction of rotation just prior to the time that the washing machine cylinder is being brought to a stop. Figure 5 represents in full lines conditions when the arm 27 is at the top of its stroke, conditions when the arm 27 is at the bottom of its stroke being shown in dotted lines. It will be clear that after the arm 27 has actuated the remainder of the mechanism to move said mechanism to the position shown in Figure 5, a lowering movement of arm 27 will withdraw the ratchet segment 24 to the position indicated in dotted lines in Figure 5, in which position the second tooth of said ratchet segment, as said teeth are counted in a counterclockwise direction, will be in a position to operate the pawl 23.

When cam 29 rotates sufficiently to again raise the arm 27 to the top of its stroke, said arm acting through the ratchet segment 24 will move lever 31 another step in a counterclockwise direction. The handle 13 will be moved synchronously with the lever 31 by reason of the connection of lever 31 with shaft 14 and lever 44, which lever 44 operates the handle 13. In the position shown in Figure 6, that is—when a high portion 30 of the cam 29 has moved the arm 27 to the top of its stroke, the switch mechanism carried by the switch block 37 will be out of contact with the fingers 40, 41, 42 and 43, whereby the electrical circuit of the driving motor 47 will be broken. At this time, also, the rod 36 will be at the limit of its movement in a left-hand direction as the parts are viewed in Figures 3 to 6 inclusive, whereby the brake mechanism controlled by said rod 36 will be fully applied. It will be clear, therefore, that when the parts have been moved to the position shown in Figure

6 the driving effect of the motor 47 will be nullified and the brake mechanism controlled by rod 36 will positively bring to a stop the moving mechanism carrying the cam 29.

It will be observed from the discussion above, that in producing automatic stopping of the moving mechanism, the operator need perform only a simple operation on a single member, that is to say—the operator will move the handle 13 through a small angle represented by the letter X. This actuation, since it allows pawl 23 to move in a cooperative relationship with the ratchet segment 24, will put the parts in position so that the speed of the driving motor will be reduced and the brake rod 36 will be actuated to lightly apply the brake mechanism. Therefore, when the cam 29 results in further actuation of the arm 27, the rod 36 will be actuated to fully apply the brakes and electrical current of the driving motor will be disconnected.

Though the machine described above is designed primarily for the automatic stopping of moving mechanism at predetermined points without shocks, said mechanism adapts itself for hand operation if circumstances should render immediate stoppage desirable. Should it be desired to stop the machine at any instant, all that is necessary is to move the handle 13 to the position shown in Figure 6. By reason of the abutting relation between portions 45 and 46 of the escape lever 20 and lever 31 respectively, said lever 31 will be moved to the position shown in Figure 6, in which the electrical connections to the motor 47 will be broken through the contact fingers 40, 41, 42 and 43 and the brake mechanism will be fully applied by reason of the movement of rod 36 to the left, as shown in Figure 2. If it should be desired to merely cut down the time in stopping, the handle 13 may be moved from its running position as shown in Figure 3, to the vertical position shown in Figure 5, which will so locate the parts that when the next high part 30 of the cam 29 again engages roller 28 of the arm 27, the mechanism will be stopped by reason of the fact that the raising of the arm 27 will bring the parts into the position shown in Figure 6, in which the electrical circuit of the motor is interrupted and the rod 36 applies the brake mechanism.

It is conceivable that due to accident or due to the fact that the cam 29 is not properly positioned relative to the moving mechanism to be controlled, said moving mechanism might not stop in exactly the proper position. To provide for this contingency the switch can be used as a regular inching switch by moving the handle 13 from full running position to the position shown in Figure 4, after which the next high portion

30 of the cam 29 which engages roller 28, will move the mechanism to produce slow movement of the member carrying cam 29 and light braking effect of rod 36, as shown 5 in Figure 5. By proper manipulation of handle 13 between the position shown in Figure 5 and the position shown in Figure 6, the mechanism can be inched along and readily stopped at any desired position.

10 As referred to above, when the rotating cylinder has been brought to rest with one of the compartment doors 55 in registry with the opening of door 58, access may be readily had to said compartment. When it 15 is desired to move the cylinder through part of a revolution whereby to gain access to another compartment, the cylinder door 55 will be closed but the shell door 58 may remain open. The operator will then move 20 the master switch lever 13 to the position shown in Figure 5 and close the switch 59 (Figure 9). The cylinder will rotate until the next high portion 30 of the cam 29 operates the lever 27. The raising of the 25 lever 27 by said next high portion 30 will result in the oscillation of the segment 34, resulting in the movement of the switch block 37 to open the circuit of the driving motor. Inasmuch as the high portions 30 30 are located in position to cause the stoppage of the cylinder at the proper points relative to the door 58, each compartment may be unloaded in succession without the necessity of closing the shell door 58 between successive movements of the cylinder.

Though a preferred embodiment of the present invention has been described in detail, it will be clear that many modifications will occur to those skilled in the art. It is 40 intended to cover all such modifications that fall within the scope of the invention as defined by the appended claims.

What is claimed is:—

1. In a washing machine, a shell including a door, a rotary cylinder mounted within said shell, said cylinder having a plurality of circumferentially spaced doors, propelling means for said cylinder, electrical controlling means for said propelling means, said electrical controlling means being responsive to the position of said shell door, operating means controlled by said propelling means and switch and brake means controlled by said operating means, 45 means responsive to the movement of said cylinder for controlling the relationship between said propelling means and said operating means, and means for nullifying the cooperative relationship between said shell door and said electrical controlling means.
2. In a washing machine, in combination, a shell including a door, a rotary cylinder having a plurality of circumferentially disposed doors each adapted to register with 50 said shell door, brake control means for said

cylinder, electric switch means, operating means for said brake control means and said switch means, automatic mechanism for moving said operating means, said automatic mechanism comprising a movable 55 member responsive to the motion of said cylinder, means for interrupting the operative connection between said motion responsive means and said operating means, propelling means for said cylinder, electrical controlling circuits for said propelling means, said electrical controlling means including a circuit closer responsive to the position of said shell door, and means for shunting said circuit closer whereby said propelling means may operate independently of said shell door.

3. In combination, an enclosing member including a door, a rotary member within said enclosing member, said rotary member having a plurality of compartments each of which is adapted to be brought into registry with said door, propelling means for said rotary member, stop mechanism for said rotary member comprising brake control means, electric switch means, operating means for said brake control means and said switch means, means for moving said operating means in progressive steps, a control member for controlling the connection between said moving means and said operating means, an electrical controlling circuit for controlling said propelling means in response to the position of said door, and means for nullifying the cooperative relationship between said door and said controlling circuit.

4. In combination, an enclosing member having a door, a rotary member within said enclosing member, said rotary member having a plurality of compartments each adapted to be brought into registry with said door, propelling mechanism for said rotary member, an electrical controlling circuit for said propelling mechanism, stop mechanism for said rotary member, said stop mechanism comprising brake control means, electric switch means, operating means for said brake control means and said switch means, means for communicating intermittent motion to said operating means, said communicating means being responsive to the movement of said rotary member, and an actuating member for controlling the relation between said operating means and said communicating means, said electrical controlling circuit including a circuit breaker responsive to the position of said door and means for shunting said circuit breaker.

5. In combination, an enclosing member including a door, a rotary member mounted within said casing and having a plurality of compartments each adapted to be held in registry with said door, propelling mecha-

- 5 nism for said rotary member, an electrical controlling circuit for said propelling means, stop mechanism including brake control means, electric switch means, operating means for said brake control means and said switch means, means for communicating progressive movement to said operating means, and gravity responsive means for controlling the relationship between 10 said communicating means and said operating means, said electrical controlling circuit including a circuit breaker responsive to the position of said door and means for nullifying the effect of said circuit breaker.

15 6. In combination, an enclosing member including a door, a rotary member mounted within said enclosing member and having a plurality of compartments each adapted to be brought into registry with said door, propelling means for said rotary member, an electrical controlling circuit for said propelling means, stop mechanism comprising, in combination, brake control means, electrical switch means, operating means for 20 said brake control means and said switch means, means for communicating a progressive movement to said operating means, gravity responsive means for controlling the relationship between said communicating 25 means and said operating means, an actuating member for said gravity responsive means for permitting said communicating means to progressively move said operating means, said electrical controlling circuit being responsive to the position of said 30 door, and means for nullifying the cooperative relationship between said controlling circuit and said door.

35 7. In combination, an enclosing member having a door, a rotary member within said enclosing member, said rotary member having a plurality of compartments each adapted to be brought into registry with said door, propelling means for said rotary member, an electrical controlling circuit for 40 said propelling means, stop mechanism comprising brake control means, electric switch means, operating means for said brake control means and said switch means, means 45 operating in synchronism with said rotary member for communicating motion to said operating means, gravity responsive means for interrupting the driving relation between said communicating means and said operating means, an actuating member having a lost motion connection with said operating means for controlling said gravity responsive means, said electrical controlling 50 means being responsive to the position of said door, and means for interrupting the cooperative relationship between said controlling circuit and said door.

55 8. In combination, an enclosing member having a door, a rotary member within said enclosing member, said rotary member hav- 60 ing a plurality of compartments each adapted to be brought into registry with said door, propelling mechanism for said rotary member, an electrical controlling member for said propelling mechanism, stop mechanism for said rotary member, said stop mechanism comprising brake control means, electric switch means, operating 65 mechanism for said brake control means and said switch control means, an actuating member having lost motion connection with said operating means, means for communicating a progressive movement to said operating means, means responsive to said actuating means for controlling the operativeness of said communicating means, said electrical controlling circuit being responsive to the position of said door, and means for nullifying the cooperative relationship between said door and said electrical controlling circuit.

70 9. In combination, an enclosing member having a door, a rotary member within said enclosing member, said rotary member having a plurality of compartments each adapted to be brought into registry with said door, propelling mechanism for said rotary member, an electrical controlling circuit for said propelling mechanism, stop mechanism for said rotary member, said stop mechanism comprising brake control means, electric switch means, operating means for said brake control means and said switch means, means for communicating a progressive movement to said operating means, means for controlling the operativeness of the connection between said communicating means and said operating means, an actuating member for controlling the position of said controlling means and having a lost motion connection with said operating means, said electrical controlling circuit being responsive to the position of said door, and means for nullifying the cooperative relationship between said electrical controlling circuit and said door.

75 10. In combination, an enclosing member having a door, a rotary member within said enclosing member, said rotary member having a plurality of compartments each adapted to be brought into registry with said door propelling means for said rotary member, an electrical controlling circuit for said rotary member, stop mechanism for said rotary member, said stop mechanism including brake control means, electric switch means, an operating member for said brake control means and said switch means, means for communicating a progressive movement to said operating means, said movement communicating means including a member for interrupting the driving relation between said moving communicating means and said operating member, an actuating member for controlling said interrupt-

80 110 115 120 125 130

ing means, said actuating member having a lost motion connection with said operating member through which said actuating member may actuate said operating member in 5 opposite direction, and connections between said communicating member and said actuating member including said operating member, whereby said communicating member may operate said actuating member only 10 after said actuating member has been moved to a certain predetermined position, said controlling circuit being responsive to the position of said door, and means for nullifying the responsiveness of said controlling 15 circuit to said door.

11. In combination, an enclosing member having a door, a rotary member within said enclosing member, said rotary member having a plurality of compartments each 20 adapted to be brought into registry with said door propelling means for said rotary member, an electrical controlling circuit for said rotary member, stop mechanism for said rotary member, said stop mechanism 25 including brake control means, electric switch means, operating means for said brake control means and said electric switch means, means for communicating motion to said operating means in response to movement 30 of the member to be stopped, said communicating means including a member adapted to interrupt the driving relation between said communicating means and said operating means, an actuating member for 35 controlling said interrupting means and having a lost motion connection with said operating means, said communicating means, operating means and actuating member all having portions co-axially mounted, and 40 means controlled by said operating means for moving said actuating member, said controlling circuit being responsive to the position of said door, and means for nullify-

ing the responsiveness of said controlling circuit to said door. 45

12. In combination, an enclosing member having a door, a rotary member within said enclosing member, said rotary member having a plurality of compartments each adapted to be brought into registry with 50 said door propelling means for said rotary member, an electrical controlling circuit for said rotary member, stop mechanism for said rotary member, said stop mechanism including a member the motion of which 55 is to be stopped, brake control means, electric switch means, operating means for said brake control means and said switch means, a shaft, said operating means being mounted for rotation about said shaft as an axis, 60 another shaft carried by said operating means, pawl means mounted upon said other shaft, ratchet means mounted for movement about said first mentioned shaft as an axis, actuating means for said pawl means 65 mounted for movement about said first mentioned shaft, means mounted for movement about said first mentioned shaft for communicating oscillating movement to said operating means in response to movement 70 of said member to be stopped, said operating means and said actuating means having peripherally abutting portions permitting lost motion between said actuating means and said communicating means, said operating means being rigidly connected to said shaft, means upon said shaft for communicating motion to said actuating member, 75 said controlling circuit being responsive to the position of said door, and means for 80 nullifying the responsiveness of said controlling circuit to said door.

Signed at Moline, Illinois, this fourth day of September, 1924.

FRITZ BALZER.
